UNITED STATES PATENT OFFICE.

ROBERT CHARLES CREECH, JR., OF COLUMBIA, SOUTH CAROLINA.

POCKET ORNAMENT.

Application filed June 15, 1921. Serial No. 477,773.

To all whom it may concern:

Be it known that I, ROBERT CHARLES CREECH, Jr., a citizen of the United States, residing at Columbia, in the county of 5 Richland and State of South Carolina, have invented certain new and useful Improvements in Pocket Ornaments, of which the following is a specification.

This invention relates to novelties in the 10 form of pocket ornaments for men's wear such as are usually worn in the left-hand coat pocket.

The object of the invention is to provide an inexpensive ornament of this character presenting the appearance of the bona fide article without the objectionable bulk incident to the use of such article and yet answer the same purpose.

Another object of the invention is to provide a plurality of interchangeable articles of this character whereby various types may be alternately or interchangeably used.

With these and other objects in view the invention consists in certain novel features 25 of construction as herein shown and described, and claimed.

In the accompanying drawings:—

Figure 1 represents a portion of a man's coat showing the left hand upper coat 30 pocket with the ornament constituting this invention shown applied, a portion of the pocket being broken out to disclose the mounting of the ornament in the pocket.

Fig. 2, is a transverse vertical section 35 taken on the line 2—2 of Fig. 1; and

Fig. 3 is a perspective view of one of the ornaments detached.

A pocket ornament in accordance with this invention comprises a mounting referred to generally by the reference character 40 1, and composed of a pair of inverted frustro triangular shaped holding members 2, 3, formed from two complementary sheets of cardboard or other suitable material, 45 which are arranged in abutting relation and are secured together at their sides and inner end, by stitching or otherwise. The members 2, 3, at their outer detached ends possess an inherent clamping characteristic 50 when slightly extended in opposite direction with respect to each other so as to clamp therebetween and hold projected therefrom an ornamental tip which in Figure 1 is illustrated in the form of the tips 4 of a handkerchief, and in Figure 3 as finger tips 5 of a glove.

The mounting for these tips may be of any desired shape, preferably of substantially truncated triangular contour to facilitate its ready insertion in the pocket of 60 the garment.

By securing the tips 4 or 5, in the flat mounting 1, they may be positioned in the pocket P, to project above the upper edge thereof, and present the appearance of a 65 folded handkerchief or a glove, and yet the objectionable bulk incident to the use of the completed article is avoided. The pocket P, being usually made very small and when a pair of gloves or a glove, is inserted therein, the body portion of the glove will cause the pocket to bulge outwardly and present an objectionable appearance.

Any suitable means may be employed for retaining the device within the pocket P, a pair of downturned prongs 6, being here shown carried by a rod 7, located between the upper portions of the clamping elements 2 and 3, and which is equipped with a securing eye 8 to provide for the passage 75 of stitches or other securing means for holding the rod against turning between the plies. Each terminus of the rod 7 is bent at right angles and extends through the element 2, and with which a prong 6 is 80 integral.

While handkerchiefs and glove tips are shown in the embodiment herein obviously any ornamental device which it would be desired to carry in this pocket or in any 90 other pocket for that matter may be substituted, the gist of the invention residing in the flat mounting or holding the ornament and securing it within the pocket.

The preferred embodiment of the invention is disclosed in the drawings and set forth in the specification, but it will be understood that any modifications within the scope of the claimed invention may be made in the construction without departing 95 from the principle of the invention or sacrificing any of its advantages.

What I claim is:—

1. A device for the purpose set forth comprising a pair of complementary holding elements arranged normally in abutting relation and having the sides and inner end thereof secured together, said elements at their outer ends possessing an inherent clamping characteristic when slightly extended in opposite directions with respect to each other for solely securing an orna- 105 110

ment between the outer ends of said elements, and each of said elements being flat and of inverted truncated triangular shape.

2. A device for the purpose set forth comprising a pair of complemental holding elements arranged normally in abutting relation and having the sides and inner end thereof secured together, said elements at their outer ends possessing an inherent clamping characteristic when slightly extended in opposite directions with respect

to each other for solely securing an ornament between the outer ends of said elements, and means arranged against the inner face of one of said elements and projecting through and depending downwardly at the outer face of said element for detachably securing said elements in position within a pocket. 15

In testimony whereof, I affix my signature hereto.

ROBERT CHARLES CREECH, JR.
